UNITED STATES PATENT OFFICE

2,037,063

VENTILATOR

Ralph Brown, Wilmette, Ill., assignor to The Adlake Company, Wilmette, Ill., a corporation of Illinois

Application June 29, 1931, Serial No. 547,580

5 Claims. (Cl. 98—97)

This invention has to do with ventilators, and is particularly concerned with ventilators of the type used in railway car windows.

In ventilators of this type, the screening element is constantly being subjected to driving air currents containing cinders, dust, rain, etc., with the result that, in a comparatively short time, clogging occurs and the screen must be replaced with a new one, which replacement necessitates considerable work since the ventilator has to be taken apart, the old screen disconnected, a new one fastened in its place, and the ventilator put back together again.

One object of the present invention is to provide, in a ventilator of the type described, a much needed improvement which permits the screen to be easily and quickly replaced without having to take the ventilator apart.

Another object of the invention is to provide a novel ventilator screen in the form of a thin, finely perforated sheet metal plate.

While the foregoing statements are indicative in a general way of the nature of the invention, other objects and advantages will be apparent to those skilled in the art upon a full understanding of the improved screen mounting.

In order that the invention may be readily understood, two slightly different structural embodiments of the same are presented herein, but it will of course be appreciated that the invention is capable of being embodied in still other forms coming equally within the scope of the appended claims.

In the accompanying drawings:

35 Fig. 1 is an outside face view of a sash ventilator equipped with the improvement of the invention;

40 Fig. 2 is a plan view of the outwardly projecting portion of the ventilator;

45 Fig. 3 is a horizontal section through the ventilator, taken on the line 3—3 of Fig. 1;

Fig. 4 is a vertical section, taken on the line 4—4 of Fig. 1;

50 Fig. 5 is a face view of the readily replaceable screen used in the ventilator shown in Figs. 1 to 4 inclusive;

Fig. 6 is a face view of a slightly different, optionally usable, screen;

Fig. 7 is a vertical section, taken on the line 55 7—7 of Fig. 6;

Fig. 8 is a fragmentary horizontal section, taken on the line 8—8 of Fig. 6;

Fig. 9 is an outside face view of a sash ventilator equipped with a modified form of the invention;

Fig. 10 is a fragmentary vertical section, taken on the line 10—10 of Fig. 9;

Fig. 11 is a fragmentary horizontal section, taken on the line 11—11 of Fig. 9; and

Fig. 12 is a fragmentary view of the readily replaceable screen used in the ventilator shown in Figs. 9 to 11 inclusive.

Since the improvement which forms the subject matter of this invention is obviously applicable to many different types of ventilators, the structural details of the particular ventilator shown in Figs. 1 to 4 inclusive are not to be considered as limiting the invention in any way. The ventilator shown in those views happens to be substantially the same in construction as that which is disclosed and claimed in the application for patent of Harry D. Severson filed September 12, 1930 under Serial No. 481,400, and accordingly does not require detailed description here.

The ventilator includes an elongated frame 10 which is positioned within the hollow bottom rail 11 of a sheet metal sash. The frame 10 is provided, adjacent the inner face of the rail, with a longitudinally extending guide groove 12, and is provided, adjacent the outer face of the rail, with a longitudinally extending row of ventilating apertures 13 which open into the groove 12 throughout one end only of the latter. The groove 12 contains a hollow resiliently expansible slide 14 which is slightly greater in length than the row of apertures 13 and is adapted to be shifted longitudinally of the groove by means of a finger piece 15, whereby to progressively close off all of the apertures. The slide 14 is held within the groove 12 by an inner cover plate 16, which plate is positioned directly opposite the row of apertures 13 against the countersunk edges of an opening in the inner face of the rail 11 and is secured to the frame 10 by screws 17 which pass through the edges of the opening into the frame. The cover plate 16 has an elongated slot 18 therein through which all of the apertures 13 are exposed when the slide 14 is retracted. The finger piece 15 operates in the slot 18.

The ventilating apertures 13 are exposed through an opening in the outer face of the rail 11, and a grid plate 19 is secured against the edges of the opening by a plurality of screws 20—in this particular instance, eight screws—which extend through the edges of the opening into the frame 10.

The grid plate 19 is preferably formed as a sheet metal stamping and is provided with a longitudinally extending row of ventilating apertures 55

21. The inner surface of the plate 19 is hollowed out slightly, the marginal edges of the plate being cupped inwardly toward the outer face of the rail 11. The upper edge 22 of the plate 19 is outwardly offset to a certain extent with respect to the other edges, thereby forming a thin upwardly opening pocket between the plate 19 and the outer face of the rail. This pocket is adapted to receive a replaceable screen 23, which screen may be readily inserted in or withdrawn from the pocket.

10 The screen 23 consists of a finely perforated light gauge sheet metal plate of horizontally elongated rectangular form. The screen is provided along its upper edge with an out-turned flange 24 which constitutes a finger piece by means of which the screen may be easily grasped in inserting or removing the same from the pocket. The flange 24 also serves as a stop for abutting engagement with the upper outwardly offset edge of the grid plate 19, whereby to definitely position the screen with respect to the grid plate.

15 In order to remove the screen 23 for cleaning or replacement after the perforations in the same have filled up with foreign matter to such an extent as to render the screen unserviceable, it is merely necessary to remove the two centrally disposed screws 20 in the upper row. The other screws 20 do not have to be removed because the only screws which pass through the screen are 20 the two above referred to, which screws extend through apertures 25 in the upper portion of the screen. After the screen has been removed, it may be cleaned very easily. Only a moment's time is required to replace the screening element 35 in a ventilator equipped with this improvement.

20 In Figs. 6 to 8 inclusive is shown a differently constructed replaceable screen 26. The screen 26 is of wire mesh construction and is provided along its upper edge with a thin sheet metal strip 27. The upper edge of the strip 27 is provided 40 with an outwardly projecting reversely bent flange 28 which engages with the upper edge of the wire mesh while the ends of the strip are provided with reversely bent tongues 29 which engage with the 45 ends of the wire mesh.

25 In Figs. 9 to 12 inclusive is shown a slightly modified form of the invention. In those views, the entrance 30 to the pocket in the grid plate 31 is located at one end of the grid plate instead of at the top of the same, and the location of the finger piece 32 on the screen 33 is correspondingly changed. This arrangement permits horizontal endwise insertion and withdrawal of the screen.

30 Instead of employing one or more of the screws 34 to hold the screen 33 in position, the latter may be made sufficiently narrow to slide between the upper and lower rows of screws and may be secured in position by means of a readily releasable latching device 35. The device 35 may consist 35 of an outwardly projecting tongue or embossment 36 on the screen adjacent one end of the latter, which tongue will snap resiliently into an aperture 37 in the grid plate. In order to release the screen 33, it is merely necessary to disengage the 40 tongue 36 from the edge of the aperture 37 by 45 pressing in the tongue with the point of a screw

driver or other suitable tool, whereupon the screen 33 may be easily slid out of the pocket.

I claim:

1. The combination, with a closure member, and a ventilator set into an opening in the closure member, of a grid plate for the ventilator positioned against the outer face of the closure member and provided with an exteriorly accessible pocket for the reception of a replaceable screen, the edges of said plate being turned inwardly to 5 form the pocket, and one of the edges being outwardly offset with respect to the other edges to 10 form the entrance to the pocket.

2. In a ventilator, the combination with a member having a ventilating opening therein, of an 15 apertured plate which is adapted to be positioned against the outer face of the member over the ventilating opening in the latter, a replaceable screen which is smaller than the plate and is adapted to be positioned against the apertured portion of the latter, means for attaching the plate to the member, and separate means for releasably locking the screen in position, said locking means when released permitting removal of the screen from the plate from the same side of the 20 ventilator as that against which the plate is positioned without disturbing the plate.

3. The combination with the bottom rail of a sash, and a ventilator set into an opening in the rail, of a grid plate for the ventilator positioned 30 against the outer face of the rail, said grid plate being concave toward the rail and being shaped at one edge to provide a slot opening into the cavity present between the rail and the concave face of the grid plate, a screen which is slideable 35 into or out of the cavity through the slot, and readily releasable means for locking the screen in the cavity.

4. The combination with the bottom rail of a sash, and a ventilator set into an opening in the 40 rail, of a grid plate for the ventilator positioned against the outer face of the rail and provided with an exteriorly accessible recess, means for connecting the grid plate to the rail, a screen positioned between the grid plate and the rail in said 45 recess, and means associated with the grid plate for locking the screen against removal, said locking means upon being released permitting removal of the screen from said recess in the same side of the rail as the grid plate without requiring any 50 displacement of the grid plate relative to the rail.

5. The combination, with the bottom rail of a sash, and a ventilator set into an opening in the rail, of a replaceable screen, and a grid plate for the ventilator positioned against the outer face of the rail and provided with an exteriorly accessible pocket for the reception of the screen, the edges of said plate being turned inwardly to 55 form the pocket, and one of the edges being outwardly offset with respect to the other edges to form the entrance to the pocket, which entrance permits insertion or removal of the screen from the pocket from the same side of the sash as that on which the grid plate is positioned without requiring removal of the grid plate.

RALPH BROWN.
